CLAIM

The ornamental design for an outer wall of a reactor for a semiconductor manufacturing apparatus, as shown and described.

DESCRIPTION

FIG. 1 is a perspective view of an outer wall of a reactor for a semiconductor manufacturing apparatus, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross sectional view taken along line 8-8 of FIG.

6; and,

FIG. 9 is a cross sectional view taken along line 9-9 of FIG. 6.

The broken lines shown in the drawings represent portions of the outer wall of a reactor for a semiconductor manufacturing apparatus that form no part of the claimed design.
